REUBEN A. McCUALEY, OF BALTIMORE, MARYLAND.

Letters Patent No. 60,919, dated January 1, 1867.

IMPROVEMENT IN PUMPS.

The Schedule referred to in these Letters Patent and making part of the same.

TO ALL WHOM IT MAY CONCERN:

Be it known that I, REUBEN A. McCUALEY, of the city and county of Baltimore, in the State of Maryland, have invented a new and improved Pump; and I do hereby declare that the following is a full and exact description thereof, reference being had to the accompanying drawing, and to the letters of reference marked thereon. The nature of my invention consists in the peculiar construction of a double-acting submerged pump, to raise and force water or other liquids.

To enable others skilled in the art to make and use my invention, I will proceed to describe its construction and operation.

In the drawings, A represents pump proper, B a central chamber, in which the piston-rod, C, and its hollow cylindrical head, D, play. On each side of this chamber there are others, E and F, which may be of any desirable shape and size to bring about economy and a proper working of the pump. The part A is secured in any suitable way, say by bolts, screws, nuts, &c., to its bottom plate, a, to which is attached a strainer, b, having a chamber, d. Through plate a there are two openings, e and f, over which are two valves, g and h. In the top part of A, or its top plate p, there is an opening, i, for the piston-rod C to pass through; it has a neck, G, as a guide for the working of the piston. There are also two other openings, j and k, in the aforesaid plate p, over which, also, are two valves, l and m, which open into a chamber, H, part of an upper metallic connection, I, to be secured to A by bolts, screws, nuts, &c. Into this is fitted a wooden pipe, J; it may be a metal one, if desired. At the joints of each section of J, I put a metal sleeve, n, having a projection, o, through which there is an opening, q, to guide the rod K, which is a continuation of piston-rod C; this rod extending upwards, and connecting with any suitable lever or rock-shaft, crank, &c., care being taken to give suitable play for said rod K. The sleeves n perform two offices. They secure the joints and hold the sections together, and are guides to rod K. They may be so constructed, in being adjusted, as to have a strong binding effect on the upper and lower ends of adjacent sections. Through the upper end of central cylinder B there is an opening, as shown at r, and at the bottom of it there is another, s.

The operation of the pump is as follows: In the drawing the piston D is represented as descending, hence valve h is down, closing hole f, whilst the water in B is forced through s up chamber F, and out of k, opening valve m into chamber H or stock tube J. This also shuts down valve l, and opens valve g, letting the water into the other chamber, E. When the movement of the piston is reversed, or goes up, valve m shuts down, h is opened, g also closes, and l opens, and the fluid in E and top part of B is forced through j into H, thus causing, on each stroke, a flow through tube J. The upper works of pump need no description. The advantages of the construction of my invention, as to economy and efficient working, are too obvious to need comment.

Having thus described my invention, what I claim as new, and desire to secure by Letters Patent of the United States, is—

1. The pump A, with its side chambers E and F, piston chamber B, openings o and r, receiving and discharging ports e, f, j, and k, arranged, constructed, and operating in the manner substantially as shown and described, and for the purpose set forth.

2. In combination with said pump, the pipe J and the connecting guide sleeves n, constructed, arranged, and operating in the manner substantially as shown and described, and for the purposes set forth.

REUBEN A. McCUALEY.
